UNITED STATES PATENT OFFICE.

ADOLPH G. KUPETZ, OF NEW YORK, N. Y., ASSIGNOR, BY MESNE ASSIGNMENTS, TO
UNDERWOOD COMPUTING MACHINE COMPANY, OF NEW YORK, N. Y., A CORPORA-
TION OF NEW YORK.

TYPE-WRITING MACHINE.

1,186,516.

Specification of Letters Patent.

Patented June 6, 1916.

Application filed November 18, 1913. Serial No. 801,579.

To all whom it may concern:

Be it known that I, ADOLPH G. KUPETZ, a citizen of the United States, residing in borough of Bronx, in the county of New York, 5 city and State of New York, have invented certain new and useful Improvements in Type-Writing Machines, of which the following is a specification.

My invention relates to means for returning the carriage of a typewriting machine 10 or a combined typewriting and computing machine to begin a new line.

A feature of the invention is the provision of means to automatically apply the driving power of a return motor to return the carriage when it reaches the end of its travel in letter-feed direction, the limit of travel being variable by means of the usual adjustable margin stop.

Another feature of the invention relates 20 to the pneumatic buffer device for effecting an easy stop of the carriage at the completion of its return movement, said buffer device connected to the adjustable right-hand 25 margin stop and thereby automatically adjusted to insure a uniform action for all stopping positions of the carriage.

An electric motor may be connected through a belt to a line-space lever for 30 turning the carriage and imparting line-space rotations to the platen. The operation of the motor is controlled by a switch, which may be actuated by a rock shaft and intermediate connections, said rock shaft journaled in the machine frame in front of and 35 parallel with the platen, and having fixed thereto a parallel rack along which is adjustable the usual left-hand margin stop slidably mounted on the rock shaft. Said margin 40 stop carries a cam in the path of a co-operating cam on the traveling carriage, the cam on the carriage operating to swing the rock shaft and close the switch to start the motor, to effect the return movement of the carriage. 45 The automatic return of the carriage is useful, for instance, in tabular work where the last figures or characters of the written lines are in a vertical column, or wherever the written characters are in vertical alignment at the right-hand side of the work-sheet.

To open the motor circuit when the carriage has about completed its return travel, the right-hand margin stop has connected 50 for adjustment therewith a rock arm splined

on said rock shaft in position to be actuated by a cam on the carriage to rotate the rock shaft in the reverse direction, and thereby open the motor circuit. Immediately after the circuit is opened, a lug on the carriage 60 engages the plunger of a pneumatic buffer connected to the margin stop and effects an easy slowing down and stopping of the carriage. The return motor is also manually controlled and may be operated to return the 65 carriage from any position by means of a finger-key, which may be connected through a trip to a vertical plunger which rocks the said rock shaft controlling the motor switch, said trip automatically releasing the plunger 70 when the key is depressed, thus permitting the plunger to return so that the switch may be opened automatically and independently of the position of the key.

I do not claim as my invention, anything 75 disclosed in the application of Frederick A. Hart, Serial No. 641,117.

Other features and advantages will hereinafter appear.

In the accompanying drawings, Figure 1 80 is a perspective view illustrating one form of my invention applied to an Underwood typewriting machine. Fig. 2 is a sectional side elevation view. Fig. 3 is a detail elevation showing a key lever, plunger and trip 85 for manually closing the motor circuit. Fig. 4 is a fragmentary perspective view showing the left-hand margin stop and the means on the carriage for actuating the stop to close the motor circuit. Fig. 5 is a similar view of 90 the right-hand margin stop, and co-operating means for opening the motor circuit. Fig. 6 is a part sectional view of the pneumatic buffer and actuating means therefor.

A rotary platen 1 is fixed to an axle 2 95 journaled in a platen frame 3 which may be shiftable to upper and lower case positions in the carriage 4. Type-bars 5 pivoted on a fulcrum rod 6 are adapted to swing upwardly and rearwardly, to cause the types 100 thereon to strike against the front face of the platen. The types are actuated by keys 7 pivoted at 8 and connected through bell cranks 9 to the type-bars.

The carriage 4 may be driven in letter-feed 105 direction by the usual carriage spring (not shown), the movement being controlled by escapement mechanism comprising an escapement wheel 10 driven by a pinion 11 meshing with a rack 12 on the carriage. Es- 110

capement dogs 13 coöperating with the wheel 10 are oscillated by a universal bar 14 actuated by shoulders 15 on the type-bars.

The platen 1 may be rotated either by 5 hand-wheels 16, or the usual line-space mechanism comprising a line-spacing lever 17 pivoted at 18 and having an arm to engage and move rearwardly a slide bar 19 to which is pivoted a pawl 20 which drives a line-space ratchet wheel 21 fixed to the platen axle. The line-space lever, pawl and slide bar are returned by a spring 22.

In accordance with the present invention, 15 the carriage is returned by means of an electric motor 23 connected through a belt 24 to the carriage. One end of the belt is attached to a winding drum or pulley 25 fixed to the motor shaft 26, the belt extending downwardly from the pulley 25 over a switch lever 27 around the pulley 28 carried by a bracket 29, over guide rollers 30 and 31 on a bracket 32 attached to the machine frame, the end of the band being releasably attached at 33 to a link 34 pivoted to a slide bar 35, the free end of which is upturned to engage the line-space lever 17. The switch lever 27 controls an automatic take-up mechanism which may be contained within the casing 36, to take up slack in the belt 24 20 when the carriage is returned by hand. Such mechanism, however, is not a part of the present invention.

The motor 23 may be connected to any 35 suitable source of power supply, as by means of a plug 37. A switch 38 in the motor circuit and controlling the operation of the motor, comprises a stationary contact 39 and a movable contact carried by a spring-actuated switch lever 40 mounted on a pivot 41. The 40 switch 38 is controlled through a rock shaft 42 in front of the carriage and parallel therewith, said shaft journaled at its ends in the machine frame.

The left-hand margin stop 43, which may 45 be of usual construction, is adjustable along the rock shaft 42 to vary the right-hand margin of the work-sheet or the position from which the carriage is returned, and has also a sliding connection with a rack 50 bar 44 parallel with the rod 42 and fixed to said rod so as to swing therewith. The stop 43 may comprise a dog 45 to engage the teeth of rack bar 44 and is actuated by a finger lever 46 to permit adjustment of the stop.

55 Fixed to the rack bar 44 and extending downwardly therefrom is an arm 47, the lower end of which is operatively connected to the forward end of a rod 48, the rear end of which is upturned to engage behind a finger 60 49 on the switch lever 40, and normally hold the switch open, the rod 48 being slidably mounted in stationary brackets 50.

The front rail 51 of the carriage has a block 52 formed thereon in which is housed a guide roller 53 running on a guide rail

54 fixed at its ends in the machine frame. Fixed to the block 52 is a forwardly extending arm 55 having a down-turned end 56, which, as the carriage completes its movement in letter-feed direction, engages beneath a cam 57 fixed to the margin stop 43, and thereby moves the rear end of the stop upwardly, the shaft 42 rocking with the stop. This movement of the stop 43 swings the depending arm 47 rearwardly, carrying 75 with it the rod 48, and permits the switch 38 to close, thereby establishing a circuit for the motor which is thus started, and winds the belt 24 on the drum 25, thereby operating through the slide bar 35, to actuate the line-space mechanism and return the carriage.

The motor circuit is opened and the carriage is stopped by means of mechanism associated with the right-hand margin stop 58. This stop is also slidably mounted on the rock shaft 42 and comprises a holding dog 59 in the form of a bell crank pivoted at 60 (Fig. 6), and having a laterally projecting arm 61 to engage the rack 62 formed on the 90 guide rail 54, said dog actuated by a finger-piece 63. The stop 58 is loosely mounted on the rock shaft 52 for longitudinal adjustment and also to permit said shaft to rock independently of the stop. Also mounted on the rock shaft 42 and adjustable longitudinally thereof is an arm 64 which is held against rotation independent of the shaft 42, as by means of a screw 65 engaging a groove 66 in the shaft 42. Said arm 64 carries a 100 cam 67 in the path of a lug 68 on an arm 69 fixed to the block 52 on the carriage, so that as the carriage nears the limit of its return movement, the lug 68 strikes the cam 67 and swings the arm 64 downwardly, thereby rocking the shaft 42, to swing the depending arm 47 forwardly to its initial position and through the rod 48 lifting the switch lever 40 to open the motor circuit and stop the motor. Immediately after the motor circuit has thus been opened, the depending end 56 of the arm 55 engages the end of a plunger 70 which works in a cylinder 71 secured as by means of screws 72 to an arm 73 on the margin stop 58. The cylinder and plunger form a pneumatic cushioning device or dash-pot to absorb the momentum of the carriage and bring it to an easy stop. As the plunger is moved to the right in the cylinder 71, the air behind the 110 plunger is compressed and gradually escapes through a vent 74 in the end of the cylinder. The final stopping point for the carriage is determined by the margin stop which may comprise a lug 58^a in the path of a coöperating stop on the carriage. The speed of the carriage is reduced by the buffer so that the lug 58^a stops the carriage without shock or jar. A coil spring 75 returns the plunger 115 when the latter is released from the carriage. 120

The return movement of the plunger is limited by a stop pin 76 fixed in the cylinder in the path of a stop screw 77 on the plunger rod, said pin 76 also forming a guide for the plunger rod. As the plunger cylinder is connected with the margin stop 58 and is therefore adjusted therewith, it is automatically maintained in a given relation to the switch-actuating arm 64 and also to the 10 stop lug 58^a, so that the action of the buffer is always the same regardless of the position to which the margin stop may be adjusted. The arm 64 and stop 58 are held against relative movement along the rock shaft 42 by a bracket 78 (Fig. 5). In order to permit the arm 69 to pass the cam 67 without rocking the arm 64 when the carriage is moved in letter-feed direction, said cam is pivoted to the arm 64 and is swung backwardly without moving the arm, the cam being held in operative position by a spring 79. To permit the carriage to be returned by the motor from any intermediate position, the key lever 80 is provided. This lever 25 carries a key 81 which, when depressed, swings the lever about its pivot 82 and operates through a bell crank trip lever 83 to lift a plunger rod 84, which extends beneath the rack bar 44, and thereby swings 30 the rack bar upwardly and closes the motor switch 38. The trip lever 83 is pivoted at 35 to a clip 86 fixed to the rod 84. Said trip lever comprises a depending arm, the lower end of which normally rests on a ledge 87 on the lever 80, and a horizontal arm which bears against a stop pin 88 on the machine frame. The plunger rod 84 extends freely through the lever 80 and normally rests on a stationary support 89. 40 When the key 81 is depressed, the trip 83 is moved upwardly carrying with it the plunger 84, but the stop pin 88 at the same time forces the trip to rotate on its pivot 85, thereby throwing the trip off the key 45 lever and releasing the plunger from the key after the switch has been closed. The key lever, therefore, slips past the trip to the position shown in Fig. 2. A spring 90 attached at one end to the plunger and at 50 the other end to the trip 83 returns the trip after the key 81 is released, said key being returned by a spring 91. As the key lever returns, it engages a collar 84^a on the plunger 84 and insures the return of the plunger. The plunger rod 84 is of such 55 length as to extend from the stop 89 to the rack bar 44 when the latter is in its normal position, as shown in Fig. 3, but being free from the rack bar permits the control of the motor switch entirely independent of the key 81. The rock shaft 42 is yieldingly held at either limit of its rocking movements by means shown in Fig. 4, comprising 60 a rock arm 92 fixed to the shaft 42 and carrying a spring detent 93, to engage in

detent openings 94, 95, when the shaft is at either limit of its swinging movements.

Variations may be resorted to within the scope of the invention, and portions of the improvements may be used without others. 70

Having thus described my invention, I claim:

1. In a typewriting machine, the combination with a carriage, a rotary platen, and line-space mechanism to rotate the platen, 75 of a rock shaft journaled in the machine frame parallel with the platen, a rack bar having a fixed connection with said shaft to rock therewith, a margin stop slidably mounted for adjustment along said shaft 80 and rack bar, an electric motor connected to operate the line-space mechanism and drive the carriage, means connected to and actuated by said rock shaft to establish a circuit for the motor when the rock shaft 85 is rocked, and means on the carriage to engage said stop and rock said rock shaft.

2. In a typewriting machine, the combination with a carriage, of a rock shaft journaled in the machine frame, a rack bar connected to rock with said shaft, a margin stop mounted on said rock shaft and adjustable along the rack bar, an electric motor, a switch for the motor, means for operating the switch when the shaft is rocked, and co-operating means on the carriage and said margin stop for automatically rocking the shaft to establish a circuit for the motor when the carriage reaches a position determined by the position of the margin stop. 100

3. In a typewriting machine, the combination with a carriage, of a stationary guide rail therefor, a rock shaft parallel with said guide rail, a margin stop adjustable along said rail and shaft, a buffer connected 105 to said stop and adjustable therewith, a member on the carriage in position to engage said buffer as the carriage nears its limit of movement determined by said stop, an electric motor to return the carriage, a switch in the motor circuit, operating connections between the switch and said rock shaft, a rock arm connected to said rock shaft, and means on the carriage to engage 110 said arm and rock said shaft to actuate the 115 switch.

4. The combination with a carriage, of a motor to drive the carriage, a switch controlling the motor, a member movable into positions to effect opening and closing of 120 said switch, means on the carriage to automatically actuate said member, a key lever, a plunger to actuate said member, a trip forming an operating connection between the key lever and plunger, and means to 125 automatically actuate the trip to release the plunger when said key lever has been actuated and thereby prevent interference between the key lever and said automatic means. 130

5. In a typewriting machine, the combination with a carriage, of an adjustable margin stop, a rock shaft along which said stop is adjustable, a rack bar connected to 5 rock with said shaft and co-operating with said stop to hold it in adjusted position, an electric motor connected to drive the carriage, a switch controlling the motor circuit, means connected to said rock shaft to 10 actuate the switch, a key lever, a plunger in position to engage said rack bar, a trip lever pivoted to said plunger in position to engage the key lever, and means to release said trip lever from the key lever when the 15 latter is actuated.
6. In a typewriting machine, the combination with a carriage, of a rocking member, stop devices adjustable along said member, cams adjustable with said stop devices, means on the carriage to engage said cams and rock said member in opposite directions, an electric motor connected to drive the carriage in one direction, a switch in the motor circuit, and means between 20 said switch and rocking member for actuating the switch when said member is rocked.
7. In a typewriting machine, the combination with a carriage, of a rock shaft journaled in the machine frame and extending in the direction of the carriage travel, an electric motor connected to drive the carriage in one direction, a switch in the motor circuit, connections between said switch 30 and rock shaft for opening the switch when the shaft is rocked in one direction and closing the switch when the shaft is rocked in the opposite direction, rock arms on said shaft, and means on the carriage to engage said arms to rock the shaft in one direction as the carriage moves forwardly, and to rock the shaft in the reverse direction when the carriage is returned.
8. In a typewriting machine, the combination with a carriage, of a rock shaft journaled in the machine frame and extending in the direction of the carriage travel, an electric motor connected to drive the carriage in one direction, a switch in the motor circuit, connections between said switch 40 and rock shaft for opening the switch when the shaft is rocked in one direction and closing the switch when the shaft is rocked in the opposite direction, rock arms on said shaft, means on the carriage to engage said arms to rock the shaft in one direction as the carriage moves forwardly, and to rock the shaft in the reverse direction when the carriage is returned and margin stops connected to said rock arms and adjustable therewith in the direction of the carriage travel to variably limit the movement of the carriage in both directions.
9. In a machine of the character described, the combination with a carriage and a motor to return the carriage from the end of a typewritten line, of a margin gage adjustable in a direction longitudinally of the carriage to variably determine the limit of the carriage travel in letter-feed direction, a support on which said gage is mounted, said support arranged to swing transversely to the direction of the carriage travel, a controller for the motor, means operable, when the carriage reaches a position in its letter-feed travel determined by the adjustment of said gage, to swing said support, connections between said support and the motor controller to actuate the latter when said support is swung during the letter-feed 70 travel of the carriage and thereby cause the motor to return the carriage, and means operable automatically during the return movement of the carriage to swing said support in the opposite direction, and thereby move the controller to inoperative position.
10. In a machine of the character described, the combination with a carriage and a motor to return the carriage from the end of a typewritten line, of a controller for the 75 motor, a margin gage adjustable in a direction longitudinally of the carriage to variably limit the letter-feed travel of the carriage, a support on which said gage is mounted, means operated by the carriage to swing said support when the carriage reaches a position during its letter-feed travel determined by the adjustment of said gage, and connections between said support and the motor controller operable by 80 said swinging of the said support to operate said controller and cause the motor to return the carriage.
11. In a machine of the character described, the combination with a carriage and a motor to return the carriage from the end of a typewritten line, of a controller for the 85 motor, a margin gage adjustable in a direction longitudinally of the carriage to variably limit the letter-feed travel of the carriage, a support on which said gage is mounted, means operated by the carriage to swing said support when the carriage reaches a position during its letter-feed travel determined by the adjustment of said gage, and connections between said support and the motor controller operable by 90 said swinging of the said support to operate said controller and cause the motor to return the carriage.
12. The combination with a carriage and a machine frame, of an electric motor to return the carriage from the end of a typewritten line, a rack mounted on the machine frame to swing transversely to the direction of the carriage travel, a left-hand margin 95

- gage adjustable along said rack to determine the limit of movement of the carriage in letter-feed direction, means on the carriage to swing said rack when the carriage reaches a position determined by the adjustment of said gage, a switch in the motor circuit, means operated by said swinging movement of said rack to close the switch and thereby energize the motor and cause it to return the carriage, and means operated by the carriage to open the motor circuit as the carriage has about completed its return travel.
13. The combination with a carriage and a machine frame, of an electric motor to return the carriage from the end of a typewritten line, a rack mounted on the machine frame to swing transversely to the direction of the carriage travel, a left-hand margin gage adjustable along said rack to determine the limit of movement of the carriage in letter-feed direction, means on the carriage to swing said rack when the carriage reaches a position determined by the adjustment of said gage, a switch in the motor circuit, means operated by said swinging movement of said rack to close the switch and thereby energize the motor and cause it to return the carriage, a right-hand margin gage adjustable longitudinally of the carriage to determine the starting position of the carriage, and means adjustable with said right-hand gage and coöperating with means on the carriage to return said swinging rack and open the switch when the carriage has reached a position determined by the position of adjustment of said right-hand margin gage.
14. The combination with a machine frame and a carriage mounted thereon to travel in letter-feed direction, of a motor to return the carriage, a rack extending in the direction of the carriage travel and mounted on the machine frame to swing transversely of the carriage, a left-hand margin gage adjustable along said rack to determine the limit of travel of the carriage in letter-feed direction, a cam on the carriage to engage said gage and swing the rack, a switch in the motor circuit, means connected to said rack and operated thereby to control the switch, the switch being operable to close the motor circuit when the rack is swung by said cam and thereby establish a circuit for the motor and cause the latter to return the carriage, means to return said rack as the carriage has about completed its return travel and thereby open the motor switch, and detents to yieldingly hold the rack in both said positions.
15. The combination with a machine frame and a carriage mounted thereon for letter-feed travel, of a motor to return the carriage, a rock shaft journaled in the machine frame and extending parallel with the direction of the carriage travel, a rack fixed to said rock shaft to rock therewith, a margin gage adjustable along said rack to adjustably determine the limit of travel of the carriage in letter-feed direction, a cam on the carriage to swing said gage and thereby rock said shaft when the carriage reaches a position during its letter-feed travel determined by the adjustment of said gage, a switch in the motor circuit, means forming a connection between the switch and said rock shaft for controlling the switch, the switch being closed when said shaft is rocked, and a cam on the carriage to engage an arm on the rock shaft to rock the latter during the return travel of the carriage to open the motor switch.
16. In a typewriting machine, the combination with a carriage, a platen thereon, and line-spacing mechanism to rotate the platen, of a motor connected to operate said line-spacing mechanism and to return the carriage, a rock shaft extending in the direction of the carriage travel, a left-hand margin gage adjustable to variably limit the letter-feed travel of the carriage, a right-hand margin gage adjustable to variably limit the return travel of the carriage, said gages each adjustable longitudinally of the carriage, arms connected to rock said shaft, one of said arms connected with the left-hand margin gage for adjustment therewith along said shaft, the other of said arms connected with the right-hand margin gage for adjustment therewith along said shaft, cam means on the carriage to engage the arm adjustable with the left-hand margin gage and rock said shaft in one direction during the letter-feed travel of the carriage and to engage the arm connected with the right-hand gage and rock said shaft in the reverse direction during the return travel of the carriage, and a switch in the motor circuit controlled by said rock shaft and operable to establish a circuit for the motor when said shaft is rocked during the letter-feed travel of the carriage and operated to open the motor circuit when said shaft is rocked during the return travel of the carriage.
17. In a machine of the character described, the combination with a carriage and a stop, of a swinging support on which the stop is mounted for adjustment longitudinally of the carriage to variably limit the travel of the carriage, means to swing said support as the carriage nears the stopping position, an electric motor, connections between the motor and carriage for returning the carriage when the motor is actuated, a normally open switch controlling the motor, and means brought into activity by the swinging of said support to automatically close the switch and cause the motor to return the carriage.
18. In a typewriting machine, the com-

bination with a carriage and an electric motor to return the carriage from the end of a line of writing, of a switch in the motor circuit, means to close said switch and cause 5 the motor to return the carriage, a rock shaft mounted on the machine frame, a margin gage adjustable along said rock shaft to determine the limit of the return movement of the carriage, an arm connected to rock with 10 said shaft, and also connected with the margin gage for adjustment therewith, a cam on the carriage to strike said arm and rock the said shaft as the carriage nears the limit of its return travel determined by said gage, and means coöperating with said rock shaft to open the motor switch.

19. In a machine of the class described, the combination with a carriage, of a motor to drive the carriage in one direction, a stop 20 to limit the movement of the carriage in said direction, said stop adjustable in the direction of the carriage travel to vary the stopping point of the carriage, a controller for the motor, means to actuate said controller, 25 comprising an arm adjustable with said stop, and means operated by the carriage to swing said arm in a direction transverse to its direction of adjustment with the stop and thereby actuate the controller to cut off 30 the power supplied while the carriage is at a predetermined distance in advance of the stopping point, determined by the adjustment of said stop.

20. In a typewriting machine, the combination with a carriage having a letter-feed travel, and a motor to return the carriage, of a right-hand margin stop supported on the machine frame and adjustable longitudinally of the carriage to determine the stopping position of the carriage at the completion of its return movement, a controller for the motor, an actuator for said controller connected for adjustment with said margin stop, and means on the carriage to operate said actuator and thereby actuate said controller to cut off the power supply from the carriage when the carriage is within a predetermined distance of its stopping position determined by said stop.

21. In a machine of the class described, the combination with a carriage and a margin stop adjustable longitudinally of the carriage to variably limit the return movement of the carriage, of an electric motor 55 to return the carriage, a switch in the motor circuit, a switch-actuating device adjustable with said stop, and means on the carriage to move said device transversely of the carriage and thereby open the motor circuit 60 when the carriage reaches a predetermined position relative to the stop.

22. In a typewriting machine, the combination with a carriage having a letter-feed travel, and a motor to return the carriage, of a right-hand margin stop supported on

the machine frame and adjustable longitudinally of the carriage to determine the stopping position of the carriage at the completion of its return movement, a controller for the motor, an actuator for said controller connected for adjustment with said margin stop, means on the carriage to operate said actuator and thereby actuate said controller to cut off the power supply from the carriage when the carriage is within a predetermined distance of its stopping position determined by said stop, and a buffer adjustable with said stop and brought into operation after the power is cut off to effect a gradual slowing down of the carriage 70 before it reaches its stopping position. 75

23. The combination with a carriage and a motor for returning the carriage from its position at the completion of a typewritten line, of a right-hand margin stop adjustable in the direction of the carriage travel to variably limit the return travel of the carriage, a rock shaft mounted in the machine frame and extending in the direction of the carriage travel, a rock arm splined on said 90 shaft and connected with said stop for adjustment therewith along the shaft, a cam on the carriage to engage said arm and rock the shaft when the carriage has reached a predetermined position during its return travel determined by the adjustment of said stop, a controller for the motor, said rock shaft connected to operate said controller and cut off the power when said rock arm is rocked, a buffer comprising a member connected to the margin stop, and a movable member positioned to be engaged by the carriage after the power has been cut off, and effect a gradual slowing down of the carriage before the final stop position is 95 reached.

24. In a typewriting machine, the combination with a carriage, of an electric motor to return the carriage, a switch to control the motor, means to automatically close the switch when the carriage reaches its limit of travel in letter-feed direction and cause the motor to return the carriage, means to automatically open the switch, a manual key to close the switch and effect the return of the carriage by the motor from an intermediate position of the carriage, and means to automatically take the switch out of the control of the key when the key has been operated to close the switch.

25. In a typewriting machine, the combination with a carriage, a rotary platen, and line-space mechanism to rotate the platen, of a motor, a motor-controlling device automatically actuated when the carriage reaches its limit of travel in letter-feed direction to cause the motor to actuate the line-space mechanism and return the carriage, means to actuate said controlling device to release the carriage from the control 125

- of the motor when the carriage has returned, a key to operate said controlling device and thereby effect the operation of the line-space mechanism and return of the carriage by 5 means operable automatically as the carriage nears the limit of its return travel to actuate said device and open the motor switch, means operable during the letter-feed travel 40 of the carriage to automatically actuate said device in a direction to close the motor circuit, a key operable manually to actuate said device and close the motor circuit, and means operated by said key to take said de- 45 vice out of the control of the key when the latter is operated, and thereby prevent interference between said key and the means for automatically opening the switch.
- 10 26. In a typewriting machine, the combination with a carriage, a platen, and line-space mechanism, of an electric motor, a connection between the motor and said line-space mechanism to operate said mechanism and return the carriage when the motor is energized, a switch in the motor circuit, mechanism for opening and closing the switch comprising means to automatically close said switch when the carriage reaches 15 its limit of travel in letter-feed direction, and means to open the switch when the carriage has returned, a key to actuate the switch-operating mechanism to close said switch when the carriage is in intermediate 20 positions, and a trip device operated by said key to take the switch-operating mechanism out of the control of the key and permit the switch to be opened while the key is in operated position.
- 25 27. The combination with a carriage movable in letter-feed direction, and an electric motor to return the carriage, of a switch in the motor circuit, a device operable in one direction to close the switch and cause the motor to return the carriage, and operable in the reverse direction to open the switch,
- 26 28. In a typewriting machine, the combination with a paper carriage, of a motor, means operable automatically when the carriage reaches a predetermined position in its letter-feed travel to bring the motor into active relation to the carriage and cause the 50 motor to return the carriage, means to automatically free the carriage from the control of the motor when the carriage has about completed its return movement, a key operable manually when the carriage is in any 55 intermediate position to bring the motor into active relation to the carriage for returning the latter, and means to take the motor out of the control of the key when the latter has been operated and thereby prevent the key from interfering with said freeing of the carriage from the control of the motor.
